ELIMINATING WATER HAZARD IN TREATING OILS

Filed April 25, 1929

Inventor
Charles D. Bayne
By his Attorney W. A. Strain

UNITED STATES PATENT OFFICE

CHARLES D. BAYNE, OF BAYTOWN, TEXAS, ASSIGNOR TO STANDARD OIL DEVELOPMENT COMPANY, A CORPORATION OF DELAWARE

ELIMINATING WATER HAZARD IN TREATING OILS

Application filed April 25, 1929. Serial No. 357,898.

The purpose of this invention is to eliminate the serious hazard due to the presence of water in commercial units for cracking or distilling petroleum oils which has been the cause of a number of disastrous explosions. The invention will be fully understood from the following description in conjunction with the drawing.

The most usual method of cracking petroleum oils on a commercial scale consists of heating the oil in a series of tubes to a high temperature, introducing the hot feed into a digesting zone or soaking drum in which most of the cracking takes place and hence conducting the liquid and vapors into a fractionating zone such as a bubble tower. The pressure in the heating tubes and the soaking drum is usually kept above 300 lbs./square inch and the pressure in the bubble tower around 50 lbs./square inch. The hot feed is ordinarily introduced into the lower portion of the soaking drum and the liquid and vaporous products leave through a common line at the upper portion of the drum.

It is common practice to steam the cracking unit before and after making a run. After a run has been completed, the equipment is steamed to reduce the quantity of oil vapors present to such a point that the danger of an explosive air-oil vapor mixture is eliminated. The purpose of steaming before a run is usually twofold. First, the steam heats up the equipment, and secondly, it lowers the oxygen content below the explosive limit. Since the equipment is generally cold when the unit is started up, large quantities of steam condense during the steaming out effected before the run. The condensed water gathers at the low points, is trapped behind the valves, etc. The bottom portions of the soaking drum and the bubble tower constitute a very dangerous trap for condensed water. During the time the unit is being brought up to operating condition, this water is often covered with a layer of cold oil and does not vaporize until the main body of oil is at a temperature considerably higher than the boiling point of water so that the vaporization occurs with a sudden vehemence. The pressure thereby produced is

in some cases higher than the soaking drum or the bubble tower can stand and in consequence bursting of some part of these vessels follows together with an explosion of the hot oil which comes into contact with air. Similar conditions may exist in various distillation equipments.

I have invented a simple method and device by which the hazard of water gathering at the bottom of distillation or cracking vessels during the starting period of a run may be successfully eliminated. For sake of illustration, the method will be described in its application to the soaking drum. In this example, the water hazard is eliminated by directing the incoming feed against the bottom head of the soaking drum in such a way that the condensed water will be stirred up. Since at the beginning of the run the temperature of the feed is raised gradually, the water which accumulated at the bottom of the drum during the steaming out operation is thoroughly stirred up and partly swept away, partly vaporized by the oil at comparatively low temperatures so that no excessive pressure will result in consequence of the sudden vaporization of water.

In the attached drawing;

Fig. 1 is a vertical section through the soaking drum provided with a device for directing the incoming feed against the bottom head;

Fig. 2 is an enlarged section of the bottom portion of the soaking drum provided with the same device;

Fig. 3 is a section similar to that of Fig. 2 showing a modified form of the device.

In Fig. 1, the character 1 designates the shell of the soaking drum, 2 and 3 designate respectively the lower and the upper man-heads. The feed is introduced through line 4 at the bottom of the drum and the liquid and vapors leave through line 5 near the top.

As seen in Fig. 2 in detail the feed is introduced at the bottom through line 4, casting connection 6, T 7, and nipple 8. The strap 9 which holds the nipple in position is welded to the drum. Plug 10 diverts the feed into the nipple which ends at the man-hole. It is obvious from the figure that the

water which tends to settle at the lowest point of the drum is constantly stirred up and vaporized or carried away by the feed before dangerous quantities could accumulate.

5 Fig. 3 shows a somewhat modified form of the invention. The numeral 11 represents a pipe of somewhat larger diameter, say 6 inches, which has been cut in two and welded to the bottom head of the drum. One end 10 of the pipe 12 is closed in order to divert the feed against the manhead.

Other similar modifications may be made and the invention may be applied to a great variety of distillation and cracking vessels as 15 well as vessels used in the chemical or other treatment of oils in which there is a danger of accumulation and sudden vaporization of water.

In the following claims the expression 20 "vessel for high temperature treatment of oil" includes all vessels of cylindrical, rectangular or other shape which are used in distillation, cracking or chemical treatment of oil effected at a temperature above the boiling point of water.

I claim:

1. In a drum for the heat and pressure treatment of hydrocarbons, a manhead neck 30 in the bottom of the drum of smaller diameter than the drum and a manhead carried by the neck, and a nozzle supported within the drum with its inlet opening through the drum and its delivery orifice positioned at the bottom of the drum to deliver fluid downwardly against a wall of the neck whereby any liquid in the neck is subject to be struck by the incoming fluid.

2. In a drum for the heat and pressure treatment of hydrocarbons, a manhead neck 40 in the bottom of the drum of smaller diameter than the drum and a manhead carried by the neck, a nozzle supported within the drum with its inlet opening through the drum and its delivery orifice positioned at the bottom 45 of the drum above one wall of the neck to deliver fluid downwardly across the neck against the opposite wall of the neck tangentially to the manhead whereby any liquid in the neck is subject to be struck by the incoming fluid.

CHARLES D. BAYNE.
